G. E. REED

ATTACHMENT FOR DOORS

Filed Feb. 4, 1922

Inventor.

George Edward Reed,
by Cipsey & Ingeland.
His Attorney's.

UNITED STATES PATENT OFFICE.

GEORGE EDWARD REED, OF GREENVILLE, MISSISSIPPI, ASSIGNOR OF ONE-HALF TO
J. A. MANN, OF GREENVILLE, MISSISSIPPI.

ATTACHMENT FOR DOORS.

Application filed February 4, 1922. Serial No. 534,142.

To all whom it may concern:

Be it known that I, GEORGE EDWARD REED, a citizen of the United States, residing at Greenville, county of Washington, Mississippi, have invented a new and useful Attachment for Doors, of which the following is a specification.

This invention relates to an attachment for doors, and consists in the novel construction hereinafter disclosed.

An object of the invention is to provide an attachment for doors comprising a strip attached to an edge of the door having relative movement in respect of the door for contacting with a face of the door frame to close the space between the door and the frame.

Another object of the invention is to provide a door with a relatively movable part movable incident to the closing of the door to contact with a face of the door frame to close the space between the frame and the door.

Additional advantages of the construction will be apparent from the following detailed description thereof taken in connection with the accompanying drawing in which—

Fig. 1 is a view of a section of the door closed, showing the movable strip in contact with the door sill.

Fig. 2 is a vertical section illustrating the mechanism of the device.

Fig. 3 is a top plan view of the attachment removed.

Fig. 4 is a bottom plan view of the strip section removed.

As the invention is illustrated in the drawing it is shown as applied to the bottom of the door to close the space between the door and the door sill. It will be understood that the invention may be applied to any form of door, such as solid doors in house construction, screen doors, refrigerator doors, door for railroad coaches and sleeping cars, garage doors, barn doors and the like, and indeed in any structure where it is desired to exclude air or dirt.

In the embodiment of the invention illustrated in the drawing the edge of the door 1 is recessed at 2, said recess 2 having a section 3 of metal tubing or the like extending from the edge of the recess to a point flush

with the side edge of the door to which the hinges of the door are attached. Mounted in the tubing 3 is a rod 4, said rod extending through the tubing 3 and being supported thereby and projecting beyond the end thereof into the recess 2.

A rocker arm 5 is pivoted on a stud 6, the stud 6 being supported transversely of the recess 2 in bearings 7 mounted at the bottom edge of the recess adjacent to the inner end of the rod 4. The rod 4 has an enlargement 8 on its inner end, said enlargement entering an opening in the upper leg of the rocker arm 5.

A strip 9 is resiliently supported in connection with the bottom edge of the door by leaf springs 10 secured to the top face of the strip at one end, the opposite ends of said leaf springs being slidably supported by supports 11 comprising U-shaped plates mounted transversely of the lower edge of the door adjacent to each side thereof. The springs 10 are so formed as to maintain the strip 9 in an elevated position.

Near the center of the upper face of the strip 9 there is a recess 12 over which is fitted a leaf spring 13 secured at one end at 14 to the top face of the strip 9 adjacent to one end of the recess, the free end of the spring 13 overlying the recess and being depressible therein.

In normal position, that is to say when the strip 9 is raised, the rod 4 projects slightly beyond the side edge of the door. Secured to the inner face of the side frame member 15 of the door is a plate 16 against which the end of the rod 4 abuts when the door is closed. Obviously, when the door is closed the rod 4 is forced inwardly rocking the rocker arm 5 to the position shown in Fig. 2, in which position the lower leg of the rocker arm contacts with the spring 13 and forces the strip 9 downwardly and in opposition to the tendency of the springs 10. Thus, as the door is closed, the lower face of the strip 9 is brought into close contact with the upper face of the door sill or lower wall of the door frame member 17, thus closing the space between the bottom edge of the door and the wall of the door frame.

The lower face of the strip 9 may be provided with a layer of felt or the like form-

ing a more perfect closure between the strip and the wall of the door frame to exclude air and dirt.

When the door is opened pressure on the 5 rod 4 is released and by the resilient action of the springs 10 the strip 9 is again drawn upwardly into contact with the bottom wall of the door, the rod 4 being moved to its outer position by the action of the spring 13.

10 It will be noted that by reason of the yielding contact between the lower leg of the rocker arm 5 and the strip 9, due to the provision of the spring 13, the space through which the strip is passed in its 15 downward movement will be varied to suit the requirements for the closure of the space between the bottom edge of the door and the wall of the door frame, which space obviously may be varied by reason of shrinkage 20 or expansion of the door. In other words, the action of the device is such that under all conditions the strip is moved sufficiently to effect a tight closure between the door and the adjacent wall of the door 25 frame.

In order to give neat appearance and also to support and guide the strip 9 a metallic strip 18 is formed about the lower marginal edge of the door, said strip extending downwardly from the lower edge of the door and over the upper marginal edge of the strip 9. This strip 18 not only entirely conceals 30 the juncture between the door attachment and the mechanism for operating it, giving 35 neatness of appearance to the structure, but also constitutes a frame and guide for holding the strip in alinement with the door so that it may be readily raised and lowered in the performance of its functions.

40 I am aware that the invention may be modified in certain particulars without departing from the spirit and scope thereof, I do not limit myself therefore to the exact details of construction shown and described.

45 What I claim and desire to secure by Letters Patent, is:—

1. The combination of a door frame, a door hinged in the frame, a strip removably secured to each side of the lower end of the 50 door, a number of springs supported for sliding movement by the lower end of the door between said strips, a transverse strip supported by said springs between said metallic strips and having a recess in its upper 55 side between said strips, an additional spring supported by said transverse strip and arranged to operate in said recess, a lever supported by the door above said additional spring and said recess, and means 60 for actuating said lever as an incident to the closing of the door to cause said additional spring to move said transverse strip

downwardly toward the lower part of the door frame in opposition to said first named 65 springs.

2. The combination of a door frame, a door hinged for swinging movement in the door frame, a number of springs, means in connection with the lower end of the door for supporting said springs for sliding movements, a transverse strip attached to said springs and having a recess in its upper side between said springs, an additional spring supported by said strip and arranged to operate in said recess, a bell crank lever supported by the door having one arm 70 thereof arranged to contact with said additional spring and being operable to cause said additional spring to press said strip downwardly in opposition to said first-named springs, and an element supported by the door and arranged to engage the door frame as an incident to the closing of the door to operate said lever.

3. The combination of a door frame, a door supported for swinging movements in the door frame, a transverse strip below the lower edge of the door and having a recess in its upper side about midway of its length, springs supported by the door for supporting said transverse strip close to the bottom edge of the door, an additional spring supported by said strip and arranged to operate in said recess, and mechanism supported by the door and arranged to be operated by the door frame as an incident to the closing of the door to cause said additional spring to press said strip downwardly toward the lower end of the door frame in opposition to said first-named 90 springs.

4. The combination of a door frame, a door hinged for swinging movement in the door frame, supports carried by the lower end of the door, a strip below the lower end of the door, springs in connection with said strip and mounted for sliding movements in said supports and exerting their power to raise said strip toward the lower end of the door, an additional spring supported by said strip between said first-named springs, a bell crank lever supported by the door above said strip and having one end contacting with said additional spring, and a rod supported by the door above said strip and having one end engaging said lever and the opposite end arranged to engage the door frame as an incident to closing of the door and to be operated thereby to cause said lever and said additional spring to move 110 said strip downwardly toward the lower end of the door frame.

GEORGE EDWARD REED.
